UNITED STATES PATENT OFFICE.

JOHN C. HARING, OF JERSEY CITY, NEW JERSEY.

CASE FOR PENCILS.

SPECIFICATION forming part of Letters Patent No. 292,909, dated February 5, 1884.

Application filed December 5, 1883. (No model.).

To all whom it may concern:

Be it known that I, JOHN C. HARING, of Jersey City, in the county of Hudson and State of New Jersey, have invented a new and 5 useful Improvement in Cases for Pencils and other Implements, of which the following is a description, reference being had to the accompanying drawings.

This invention relates more particularly to 10 pencil-cases; but is also applicable to cases for tooth-picks, knives, and such other implements as may be fitted to cases, within which they may move back and forth in such manner as to be capable of protrusion therefrom 15 for use, and of being sheathed therein when not in use.

The invention consists in certain means, whereby the movement within the case proper, or, as it is commonly termed, the "receiver" 20 of what is variously termed the "follower" on the "carrier" is controlled, and the follower or carrier is firmly locked or secured either in position to keep the pencil or implement sheathed, or to keep it protruded for 25 use.

Figure 1 in the drawings exhibits a longitudinal section of a pencil-case constructed according to my invention, but shows the exterior of the pencil-holder and its carrier. Fig. 30 2 exhibits a longitudinal section of the receiver, but shows the exterior of the parts contained therein, and represents the pencil as protruded for use. Fig. 3 is a view corresponding with Fig. 2, except that the pencil, 35 being sheathed, is invisible. Fig. 4 represents external longitudinal views of the two principal parts of the device which lock and control the carrier. Fig. 5 represents the opposite sides of the parts shown in Fig. 4. Fig. 40 6 is a transverse section of the case on a larger scale than the other figures. Fig. 7 is a view corresponding with Fig. 2 of a modification of my invention.

A is the case proper or receiver, consisting 45 of a tube of brass or other metal, which may be incased with an external shell of gold, india-rubber, or other material.

B is the carrier or follower, to which the pencil-holder C or other implement is attached, or by which it is carried, which will 50

be hereinafter referred to as the "carrier," and which, being preferably of cylindrical form, has its exterior so much smaller than the interior of the receiver that when it is in the receiver there is room between it and the receiver for the locking and controlling device by which the movement of the carrier is controlled and prevented. This carrier has provided on its exterior a laterally-projecting pin, a. 55

The locking and movement-controlling device consists of a sliding tube, D, fitted with a cap or head, D', a fixed guide, E, and a spiral spring, F. The tube D has its lower portion completely cylindrical, and fitting loosely between the interior of the receiver and the exterior of the carrier, and it has an upward semi-tubular prolongation or guide, D², which will presently be more fully described, and which, as shown in Figs. 1, 2, 3, 4, is furnished 60 with a neck, D³, to which is firmly secured the head or cap D'. The fixed guide E, which is firmly and immovably secured to the interior of the receiver, has at its upper end a collar, b, which corresponds in circumference with the 65 tube D, and the portion below this collar is semi-tubular, and the exact counterpart of the prolongation or guide D² of the sliding tube D. The said guide E and the tube D might be considered as two parts of one tube were it not 70 that the latter is capable of sliding lengthwise within the receiver and the former is immovable therein. The longitudinal matching edges of D² and E are quite straight and parallel with the axis of the case on one side, as 75 shown at g in Fig. 5; but on the other side they are formed as shown in Figs. 2, 3, 4—that is to say, with the longer central portions, c c, the end portions, d d, straight and parallel with the axis of the tubes, but with inclined 80 portions e e between d d and c c. At the top of the upper incline e of the guide E, there is a notch, f, and at the bottom of the lower incline e of the sliding tube D is a notch, f'. The straight edges g g and e e are so close together that while the tube D is free to slide in 85 the receiver it is prevented from turning therein; but the edges c c are so far apart that they 90 always form a passage for the pin a on the carrier, though this pin can only pass in and out 95 100

of the said passage *c* when the edges are separated at *e e*, as shown in Fig. 3, and this separation is effected by the movement of the tube *D*, by pressure of the thumb or finger on the 5 head *D'*, the said edges *c c*, both at top and bottom of the passage being, when there is no pressure thus applied on the head, brought together, as shown in Fig. 2, and so made to close the passage *c* at top and bottom by the 10 action of the spring *F*, which, as shown in Figs. 1, 2, 3, is coiled around the neck *D'* of the sliding tube between the upper edge of the fixed collar *b* and the lower edge of the cap or head *D'* of the sliding tube.

15 When the pencil or instrument is sheathed, as shown in Figs. 1 and 2, the pin *a* on the carrier is on the notch *f*, and when the pencil or implement is protruded for use, as shown in Fig. 3, the pin *a* is in the notch *f'*. Fig. 2 20 shows the sliding tube *D* as held back by the spring, so that passage between *e e* is closed, and the pin is locked in the said notch and the carrier held back in the receiver; but Fig. 3 shows the head *D'* still depressed, as it was, to 25 let the pin *a* pass into the lower notch, *f'*. On the removal of the pressure from above *D'* the spring draws up the tube *D* and closes the passage *e*, and so locks the pin *a* in the notch *f'*.

To produce the protrusion of the pencil from 30 the case for use, the case is held with the head upward, and pressure is applied to the head to open the passages at *c c* for the pin *a*, and the carrier drops by gravitation till the said pin stops in the notch *f'*. To produce the 35 withdrawal or sheathing of the pencil into the case, the latter is held head downward, and the head is pressed upward to open the passage at *c c*, when the carrier descends by gravitation until the pin reaches the notch *f*. It 40 will be seen that the notches *f f'* limit the movement of the carrier.

In writing, the pressure on the receiver is prevented from producing the inward movement of the pencil by the pin *a* bearing against 45 the fixed inclined edge *c* above it. Any tend-

ency to run up this incline forces the pin over against the upright side of the notch *f'*, and as the sliding tube cannot turn the pin is arrested; hence the locking of the carrier is positive.

The example of my invention shown in Fig. 7 only differs essentially from that shown in the other figures in that the spring *F* is applied between the upper end of the tip-piece *G* and the lower end of the tube *D*, instead of being like the spring *F* in the other figures applied to the upper parts of the tube *D* and receiver.

What I claim as my invention, and desire to secure by Letters Patent, is—

1. The combination, with the receiver and a carrier furnished with a pin or lateral projection, of a fixed guide within the receiver and a movable guide between the receiver and carrier, the two said guides having between them a passage for the said pin or projection on the carrier, and a spring and pressure-cap for operating said movable guide for opening and closing said passage, substantially as herein described.

2. The combination, with the receiver and a carrier furnished with a pin or lateral projection, of a fixed guide within the receiver, a movable guide between the receiver and carrier, and a spring and pressure-cap applied to the said movable guide, the said guides comprising straight and inclined portions, and being notched for the passage and stoppage of the said pin or projection, substantially as herein described.

3. The combination of the receiver *A*, the carrier *B*, having a projection, *a*, the stationary and movable notched guides *ED'*, having a passage, *c e e*, between them for the said projection, the pressure-cap, and the spiral spring, substantially as herein described.

JOHN C. HARING.
